UNITED STATES PATENT OFFICE.

JOHN A. ALEXANDER AND FRANK K. BERRY, OF BATTLE CREEK, MICHIGAN, ASSIGNORS
TO A. B. STOVE COMPANY, OF BATTLE CREEK, MICHIGAN, A CORPORATION OF
MICHIGAN.

DESIGN FOR A GAS-RANGE.

41,620.

Specification for Design.

Patented July 25, 1911.

Application filed June 16, 1911. Serial No. 633,608. Term of patent 14 years.

To all whom it may concern:

Be it known that we, JOHN A. ALEXANDER and FRANK K. BERRY, both citizens of the United States of America, residing at Battle Creek, in the county of Calhoun and State of Michigan, have invented a new, original, and ornamental Design for Gas-Ranges, of which the following is a specification, reference being had therein to the accompanying drawing, forming part thereof.

The figure is a perspective view of a gas range, showing our new design.

We claim:

The ornamental design for a gas range, as shown.

JOHN A. ALEXANDER.
FRANK K. BERRY.
